US00D949417S

(12) **United States Design Patent** (10) Patent No.: **US D949,417 S**
Khubani et al. (45) Date of Patent: **** Apr. 19, 2022**

(54) **ATTACHMENT TO AN ELECTRICAL STIMULATION DEVICE**

(71) Applicant: **Health Bloom, LLC**, Miami Beach, FL (US)

(72) Inventors: **Ajit Khubani**, Saddle River, NJ (US); **Damian Mucaro**, Hackensack, NJ (US); **Paul Dowd**, Scarsdale, NJ (US)

(73) Assignee: **Health Bloom, LLC**, Miami Beach, FL (US)

(**) Term: **15 Years**

(21) Appl. No.: **29/756,870**

(22) Filed: **Oct. 30, 2020**

(51) LOC (13) Cl. **28-03**

(52) U.S. Cl.

USPC **D24/215**

(58) **Field of Classification Search**

USPC D24/200, 209, 211, 212, 213, 214, 215; D7/393; D8/307, 310, 378; D9/435, 439

CPC . A61H 2201/0119; A61H 7/002; A61H 7/007

(57) **CLAIM**

The ornamental design for an attachment to an electrical stimulation device, as shown and described.

DESCRIPTION

FIG. 1 is a top, front, left side perspective view of an attachment to an electrical stimulation device according to our new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

1 Claim, 7 Drawing Sheets
